212,840

DISPENSER FOR COCKTAIL MIXES

J. Russell Price, Esmond, R.I., assignor, by mesne assignments, to Textron Inc., Providence, R.I., a corporation of Rhode Island

Filed Feb. 17, 1967, Ser. No. 5,861

Term of patent 14 years

(Cl. D94—3)

FIG. 1

FIG. 2

FIG. 3

FIGURE 1 is a side elevation of a dispenser for cocktail mixes showing my new design, the aperture being present only on the side shown,

FIGURE 2 is a front view left of FIGURE 1, and FIGURE 3 is a front view right of FIGURE 1.

I claim:

The ornamental design for a dispenser for cocktail mixes, shown and described.

References Cited

UNITED STATES PATENTS

2,695,023 11/1954 Brown.

3,253,592 5/1966 Von Pechmann.

OTHER REFERENCES

The Game Room Catalog, rec'd Nov. 9, 1955, "Wiskometer" on p. 29.

WALLACE R. BURKE, Primary Examiner.

J. COOPERSMITH, Assistant Examiner.